UNITED STATES PATENT OFFICE.

FRANK B. MERRY AND JESSE D. WARE, OF SAVANNAH, GEORGIA.

TURNING AND FLUTING MACHINE.

1,223,597.

Specification of Letters Patent. Patented Apr. 24, 1917.

Application filed September 7, 1916. Serial No. 118,847.

To all whom it may concern:

Be it known that we, FRANK B. MERRY and JESSE D. WARE, both citizens of the United States, and both residing at Savannah, in the county of Chatham, State of Georgia, have invented certain new and useful Improvements in Turning and Fluting Machines, of which the following is a specification.

10 This invention relates particularly to a machine of the general type disclosed in our prior Patent No. 1,175,969, March 21, 1916, for turning columns or posts of wood from rough material to give them a round, tapered, or other desired form.

15 This invention has for its object the provision of a machine of this general type capable of producing grooves, flutes, or ribs on round or tapered columns or the like of 20 various diameters as desired for purposes of ornamentation.

25 The invention has further for its object the provision of a sliding frame carrying a cutter for forming peripheral beads on the column, caps, or bases, which frame is adjustable into and out of operative position so as not to interfere with the operation of the fluting or grooving mechanism.

30 Another object of the invention resides in the provision of a carrier for the cutter carriage which is adjustable toward and away from the machine so as to accommodate work of various diameters, together with a templet cooperating with said carrier in any 35 adjusted position.

35 A still further object of this invention is to provide means for automatically and manually controlling the operation of the machine so that accuracy and simplicity thereof is insured.

40 These objects together with attendant advantages will be apparent as the invention becomes better understood by reference to the accompanying specification and drawings forming a part thereof, throughout the several views of which like characters of reference have been used to designate like parts.

45 Referring generally to the drawings Figure 1 is a side elevation of a machine embodying our improvements, parts thereof being broken away for the sake of clearness.

Fig. 2 is a plan view thereof.

50 Fig. 3 is a view on an enlarged scale, partly in section, showing particularly the 55 manner of mounting the cutters in the lathe carriage.

Fig. 4 is an enlarged detail view of the means for locking the carriage carrier in a position parallel to the lathe centers.

Fig. 5 is a detail view of the fluting cutter and the control therefor.

Fig. 6 is an enlarged detail view of the clutch for the speed reducing mechanism of the head stock.

Fig. 7 is an end view of the machine. 65

Fig. 8 is a transverse sectional view of the carriage carrier and templet taken on the line Y—Y of Fig. 10.

Fig. 9 is a rear view showing the carrier and templet controls. 70

Fig. 10 is a plan view of the mechanism shown in Fig. 9.

Fig. 11 is a transverse sectional view on the line X—X of Fig. 2.

Fig. 12 is a plan view of the bead cutter. 75

Fig. 13 is a detail view of the mounting for the speed reducing mechanism.

Referring now more particularly to the drawings the lathe bed 1 may be of any suitable construction, and is supported on legs 2 placed at suitable intervals throughout the length of the lathe bed. Mounted on the opposite ends of the lathe bed are the head stock 4 and the tail stock 5, the latter of which may be constructed in any usual or well known manner. The head stock 80 preferably comprises a shaft 6 having a fast pulley 7 and a loose pulley 8 carried thereby. For the purpose of providing a relatively slow drive for the work, a supplemental drive pulley 9 may be provided on the shaft 10 extending at right angles to the main shaft of the head stock and carrying a worm 11 meshing with the worm wheel 12 mounted on the end of the head stock shaft. This 85 reduction mechanism may be thrown into and out of operative position by means of the lever 13 pivoted to the head stock in any desired manner at one end and having a spring lock 14 for holding the worm in position. A spring controlled clutch member 15 slidably secured by a pin and slot connection to the shaft 10 may be employed to operatively couple the worm wheel 12 to the shaft. 100 Secured in any desired manner to the rear of the lathe bed there is provided a shelf 15 having suitable braces 16 cooperating with the supporting legs of the lathe bed. Mounted on the shelf 15 in a hollow carrier 17 for the lathe carriage which has mounted thereon the turning and fluting mechanisms. The turning mechanism preferably comprises a 105

Fig. 18 is a view on an enlarged scale, partly in section, showing particularly the manner of mounting the cutters in the lathe carriage. 110

- rotary cutter 18 mounted on the shaft 19 carrying a drive pulley 20 adjacent one end. The shaft 19 is grooved longitudinally at 21 and the cutter is connected thereto by keys 22 in such manner that the cutter while being operatively driven by the shaft is free to slide longitudinally thereon throughout the length of the machine so as to operate upon the work from end to end.
- 10 The shaft 19 passes through posts 24 on the lathe carriage and is journaled therein by means of the sleeve 25 formed integral with, or connected in any desired manner to the hub 26 from which the cutters 18 radiate.
- 15 Mounted on the sleeve 25 intermediate the length thereof, and preferably between the posts 24, is a friction drive pulley 27 with which the friction wheel 28 on the shaft 29 is adapted to mesh at certain times throughout the operation of the machine as will be hereinafter described. The friction wheel is secured to one end of the shaft 29 which is journaled in the pivotally mounted bracket 30. Intermediate the ends of the shaft 29 is mounted a fluting or grooving cutter 31. By reason of the pivotal mounting of the bracket 30 on one of the posts 24 it will be apparent that the fluting cutter may be brought forward into cutting position so as to form ribs, grooves or flutes on the work depending on the construction of the cutter blades, and then thrown backwardly into inoperative position.
- For moving the friction wheel 28 into engagement with the drive pulley 27 when the cutter is swung forwardly, we have shown a cam guide 32 carried by one of the posts 24 and coöperating with a suitably formed lug or set screw 32' on the bracket 30. This construction makes the control of the fluting cutter automatic, and increases the safety factor of the machine by having idle parts at rest.
- For moving the carriage longitudinally of the shaft, it is provided with a depending lug 33 having an interiorly threaded opening formed therein adapted to cooperate with the screw drive shaft 34 driven through the medium of pulleys 35 in either direction.
- 50 By reason of this screw feed it will be apparent that the carriage may be moved longitudinally so that the rotary cutter may act on the work throughout as much of the length as desired, and that the fluting cutter may also form a rib or groove for any length desired, the length of the cut being automatically controlled as will be described hereinafter.
- In order that the machine may be used for cutting tapered columns or the like, there may be provided an angle iron 36 mounted on the shelf 15 to the rear of the carrier and supporting a templet or pattern 37. For coöperation with the templet, the carriage is provided with a rearwardly pro-
- jecting portion 38 having a roller 39 on the lower surface thereof adapted to run along and be guided by the templet. For holding the roller in operative position with the face of the templet there may be used a weight 40 or other suitable device connected to the carriage carrier by means of levers 41. For permitting movement of the carrier in accordance with the design on the face of the templet there may be provided a pivot 42 extending through an opening in the carrier and having a loose sleeve 44 thereon co-operating with the sides of the carrier.
- In order that the machine may be used to operate upon columns or posts of relatively large diameters it is necessary that means for moving the rotary cutter and the fluting cutter to and from the work be provided. In the embodiment of our invention disclosed in the drawings this means is shown as comprising slots 45 formed in the upper surface of the shelf 15 through which the pivot 42 for the carrier and the eye-bolts 46 for the angle iron may pass and have relatively unrestricted lateral movement toward and from the lathe bed. For accomplishing this lateral movement of the carrier and templet in unison there may be provided a lever 47 secured to the rod 48 which is connected at suitable intervals throughout the length of the machine to lugs 49 formed on the base of the angle iron 36 through the medium of toggle links 50. The lever 47 is in turn connected with the carrier 17 by the link 51 having pivotal connection at each end. From the foregoing it will be apparent that when the lever 47 is moved toward or from the operator to accommodate the insertion of work of different diameters, that the carrier and the templet will be moved in unison in a corresponding direction. For locking the carrier in adjusted position the pivot is preferably screw threaded at its lower end and provided with a nut 52 having an operating handle or wrench 54 secured thereto. The locking means for the templet may comprise a series of eye-bolts 46 before referred to screw threaded at their lower ends and provided with nuts 55. The angle iron has locking plates 56 mounted thereon through which the eye-bolts pass and which is adapted to coöperate with the locking bar 57 having flat or cam face 58 cut thereon. When the locking bar is in the position shown in Figs. 7 and 8 the angle iron is free to move, but when the bar is swung through the medium of the handle 59 so that the circular face thereof engages the locking plates, the angle iron is clamped in its adjusted position.
- As before described, the rotary cutter 18 operates upon the work to form a round or tapered column, and the fluting cutter is then swung into position to form ornaments extending longitudinally of the column.

as desired. If it is desired to form a column having a plurality of flutes, this may be accomplished by holding the column stationary and moving the cutter 18 longitudinally thereof, the column then being turned sufficiently to permit the cutting of another flute at any desired angle to the flute or flutes already formed. In order that the carriage may be automatically controlled after it has traveled the desired length, we have shown an automatic belt shift comprising a tappet rod 60 extending substantially the entire length of the machine and supported on the carriage by the upright 61 which has the upper end thereof turned at right angles to the main body thereof as shown at 62 to form a support for the bracket 30 when the same is swung to its rearward or inoperative position. Adjustably mounted on the rod 60 are stops 64 which may be set at any desired position and which are operated by the upright 61 at the desired limits of its travel to slide the tappet longitudinally. This longitudinal movement of the tappet rod is utilized through the medium of the belt shifting member 65 to slide the driving belts from the pulleys 35 onto the loose pulley 66 in the desired order, or vice versa. As it is sometimes desired to shift the belt manually to stop the operation of the machine for various purposes, we have provided a lever 67 pivoted intermediate its length to the carrier 17 and having its opposite end connected through the medium of a bolt and slot connection 68 to a longitudinally movable rod 69 which may extend the entire length of the machine or only a portion of the length thereof to satisfy the requirements of the operator. This rod is conveniently mounted in suitable bearings on that side of the machine at which the operator ordinarily stands so that it may be manually moved longitudinally of the machine to swing the lever 67 and so shift the belts as found necessary. There may also be provided a supplemental automatic control for the belts which may comprise a clamp 70 having rods 71 adjustably mounted therein and projecting from opposite sides thereof. These rods have the ends 72 thereof turned at right angles to engage the collars or stops 64 on the tappet rod when the same are swung into operative position by means of the link 74 and the handle 75. This construction is found convenient when it is desired to produce ornamental effects on the column throughout a comparatively short portion of its length and when it is not desired to take time to adjust the stops which ordinarily control the cutter carriage. In order to properly space the grooves or flutes we preferably form the fast pulley 7 with a plurality of concentric annularly arranged perforations 76 adapted to receive a pin 77 on a spring lever 78 secured in any convenient manner to the lathe bed. By this construction the work may be held in any desired position while being ornamented and may be moved to the desired extent to properly space the ornamentations. In order that the fluting cutter 81 may cut a groove or bead longitudinally of the column and not spirally thereof, it is essential that the carrier during this operation be held against pivotal movement. This is accomplished by providing a swinging latch 79 secured to the carrier and adapted to engage a notch or depression in the arm 80 secured to the angle iron carrying the templet. This construction renders the weight 40 ineffective to move the carrier so as to cause the same to follow the contour of the templet.

After the column has been turned to the desired shape and suitably ornamented, there may be formed thereon a peripheral bead by means of the beading cutter 81 mounted on the shaft 82 suitably journaled on the frame 84 sliding in the grooved guides 85 on the lathe bed below the upper face thereof. The frame is slid vertically in the guides 85 by means of the handle 86 attached to the counter-balanced lever 87 by the shaft 88, the lever 87 being in turn connected to the frame through a link 89. For driving the beading cutter there may be employed a jack shaft 90 driven by the pulley 91 and transmitting motion to the cutter by the driver 92 and the belt 94, said belt passing around a pulley 95 on the shaft 82 and thence around the idler pulleys 96, one of which 100 may be yieldingly held in position by the spring 97. The arrangement of pulleys is such that when the frame is slid downwardly into inoperative position the belt passes loosely around the pulley 95 so that the beading cutter is not driven at this time. As soon, however, as the frame is lifted into operative position the belt is automatically tightened due to the arrangement of the pulleys and the cutter is rotated to form a bead of desired formation on the column or other piece of work carried by the lathe.

This machine may also be used for forming base or capital members by attaching a face plate of any well known construction 115 to the head stock, in place of the center, and then securing the base or capital members thereto. When so attached they may be operated upon by the vertically movable cutter and shaped in the desired manner.

While we have shown and described a machine of the type particularly adapted for working on wood it is apparent that by making minor changes in the construction of the cutters that the same machine could 125 be successfully employed for metal or stone working purposes.

Having thus described our invention what we claim is:

1. The combination with a lathe bed, of a

supporting shelf, a cutter carriage, a carrier for said carriage on said shelf, a structurally independent templet mounted directly on said shelf adjacent the carrier, means for adjusting said carrier and said templet laterally toward and from the lathe bed, and means for locking said carrier and templet in adjusted positions on the supporting shelf to prevent accidental movement thereof by 10 said adjusting means.

2. The combination with a lathe bed, of a supporting shelf, a cutter carriage, a carrier for said carriage on said shelf, a structurally independent templet mounted directly on 15 said shelf adjacent the carrier, means for simultaneously adjusting said carrier and said templet laterally toward and from the lathe bed, and means for locking said carrier and templet in adjusted positions, on 20 the supporting shelf to prevent accidental movement thereof by said adjusting means.

3. The combination with a lathe bed, of a cutter carriage, a carrier for said carriage, a pivot for said carrier, a structurally independent templet, means for adjusting said pivoted carrier and said templet laterally toward and from the lathe bed, and means for locking said pivot and said templet in adjusted positions, said locking means permitting swinging movement of the carrier 30 independently of said templet.

4. The combination with a lathe bed, of a cutter carriage, a carrier for said carriage, a pivot for said carrier, a structurally independent templet, means for simultaneously adjusting said pivoted carrier and said templet laterally toward and from the lathe bed, and means for locking said pivot and said templet in adjusted positions, said locking 35 means permitting swinging movement of the carrier independently of said templet.

5. The combination with a lathe bed, of a cutter carriage, a carrier for said carriage, a pivot for said carrier, a structurally independent templet, means for adjusting said pivoted carrier and said templet laterally toward and from the lathe bed, means for locking said pivot and said templet in ad- 45

justed positions, said locking means permitting swinging movement of the carrier in 50 the plane of adjustment independently of said templet, and means for preventing said swinging movement of the carrier.

6. The combination with a lathe bed, of a cutter carriage, a carrier for said carriage, a pivot for said carrier, mechanism for adjusting said pivoted carrier, means for locking said pivot in adjusted position, and means carried by said pivot for permitting pivotal movement of said carrier in the plane of 60 adjustment when locked in adjusted position.

7. The combination with a lathe bed, of a cutter carriage, a carrier for said carriage, a pivot for said carrier, mechanism for adjusting said pivoted carrier, means for locking 65 said pivot in adjusted position, means carried by said pivot for permitting pivotal movement of said carrier in the plane of adjustment when locked in adjusted position, and means for preventing pivotal movement 70 of said carrier.

8. The combination with a lathe bed, of a shelf projecting from one side thereof, a cutter carriage carrier and a structurally independent templet mounted on said shelf, a pivot for said carrier, means for adjusting said pivoted carrier and templet on said shelf, and means for locking said pivot and said templet in their adjusted positions. 75

9. The combination with a lathe bed, of a shelf projecting therefrom, said shelf having slots formed in the upper surface thereof, a cutter carriage, a carrier for said carriage, a pivot for said carrier, a structurally independent templet for controlling said carriage, means for adjusting said carriage and said templet on said shelf, and means passing through said slots for locking the pivot and templet in adjusted positions. 80 85

In testimony whereof, we have hereunto 90 subscribed our names.
